CLAIM

The ornamental design for a dispensing container, as shown and described.

DESCRIPTION

FIG. 1 is a top, front perspective view of a dispensing container showing our new design;

FIG. 2 is a top, rear perspective view;

FIG. 3 is a top plan view; and

FIG. 4 is a bottom plan view.

The broken line showings in FIGS. 1 and 2 are environmental only and form no part of the claimed design.

FIG. 1

FIG. 4
